UNITED STATES PATENT OFFICE.

CHARLES MILLS AND ROBERT W. HUNTON, OF NEWTON, MASSACHUSETTS,
ASSIGNORS TO THE SACO & PETTEE MACHINE SHOPS, OF SAME PLACE.

DESIGN FOR AN END CLIP FOR CARD-FLATS.

SPECIFICATION forming part of Design No. 30,885, dated May 30, 1899.

Application filed May 2, 1899. Serial No. 715,370. Term of patent 14 years.

To all whom it may concern:

Be it known that we, CHARLES MILLS and ROBERT W. HUNTON, citizens of the United States, and residents of Newton, in the county 5 of Middlesex and State of Massachusetts, have invented and produced a new and original Design for End Clips for Card-Flats, of which the following is a specification, reference being had to the accompanying drawings, forming a part thereof.

Figure 1 represents the end clip in perspective, and Fig. 2 the clip in elevation.

As shown in the drawings, the leading or material feature of our design consists of the 5 thin bar A, having parallel edges a a' , rounded corners a^2 a^3 , and arms a^4 a^5 , extending lat-

erally from the ends of the bar in the same direction parallel with each and having upturned ends a^6 , the said arms being curved upon their inner edges at a^7 , where they enter the bar. 20

Having described our invention, what we claim as new, and desire to secure by Letters Patent of the United States, is—

The design for an end clip for card-flats as 25 herein shown and described.

CHARLES MILLS.
ROBT. W. HUNTON.

In presence of—

CHAS. R. BROWN,
E. W. SABIN.
